UNITED STATES PATENT OFFICE

164,196

SYRINGE RACK

Marvin Pink, Chicago, Ill.

Application October 28, 1950, Serial No. 12,762

Term of patent 14 years

(Cl. D80—9)

To all whom it may concern:

Be it known that I, Marvin Pink, a citizen of the United States, residing at 6558 North Ridge Avenue, Chicago, State of Illinois, have invented a new, original, and ornamental Design for Syringe Rack, of which the following is a specification, reference being had to the accompanying drawing, forming a part hereof.

Fig. 1 is a top plan view of a syringe rack, showing the design of my invention;

Fig. 2 is a front elevational view thereof;

Fig. 3 is a rear elevational view; and

Fig. 4 is an end view.

I claim:

The ornamental design for a syringe rack, as shown.

MARVIN PINK.
